CLAIM

The ornamental design for a utility task vehicle as shown and described.

DESCRIPTION

FIG. 1 is a front, right-side, and top perspective view of a utility task vehicle showing my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The dashed broken lines depict portions of the utility task vehicle for which no design protection is claimed.
